RADIO FREQUENCY TRANSDUCER

Maurice Arditi, Clifton, N. J., assignor to International Telephone and Telegraph Corporation, a corporation of Maryland

Application July 22, 1953, Serial No. 369,643

16 Claims. (Cl. 333—34)

This invention relates to radio frequency transducers 15 and more particularly to transition structures from coaxial waveguides to single or parallel conductor waveguides.

Attempts have been made heretofore to provide transition couplings between coaxial waveguides and single or parallel conductor waveguides but such prior transition structures have either involved special expensive "plumbing" or elaborate and relatively expensive horn structures. It is an object of the present invention to provide a transducer for use between coaxial waveguides and single or parallel conductor waveguides which is relatively simple and inexpensive to build.

Briefly, the transducer according to the principles of the present invention comprises two conductors, one of elongated form and the other of a wider configuration such as to present a planar conducting surface facing the first mentioned conductor. The two conductors are preferably spaced apart by a layer of dielectric material to maintain them in substantially parallel relation. Energy propagated over a coaxial waveguide is transferred to the parallel conductor arrangement by providing an opening through the planar conductor, the outer conductor of the coaxial waveguide being connected to the planar conductor coaxially of the opening with the inner conductor extending through the opening in electrical connection with the first or elongated conductor. Radio frequency energy propagated along the coaxial line is transferred readily for propagation along the first and second conductors in substantially the same mode of propagation as in the coaxial line. The wave energy is transferred from the spaced conductors to a waveguide of either the single conductor type or the parallel conductor type. Where it is to be transferred to a single conductor the planar conductor is slotted along the zone underlying the elongated conductor, the slot being flared gradually away from the elongated conductor whereby the wave energy is satisfactorily launched for propagation along an extension of the single elongated conductor. For propagation along a waveguide of parallel conductors, a third conductor is disposed in parallel relation to the elongated conductor or an extension thereof and is either coupled directly to the planar conductor or is disposed in parallel relation thereto. In the latter case, the planar conductor is terminated preferably in a tapered form a short distance from the coaxial coupling.

The above-mentioned and other features and objects of this invention and the manner of attaining them will become more apparent by reference to the following description taken in conjunction with the accompanying drawings, wherein:

Fig. 1 is a view in perspective with parts cut away to show one embodiment of the invention wherein a coaxial line is coupled to a waveguide of parallel conductors;

Fig. 2 is a view in cross-section taken along line 2—2 of Fig. 1;

Fig. 3 is a view in cross-section similar to Fig. 2, showing the parallel conductors with a greater spacing;

2

Fig. 4 is a view in perspective of another embodiment of the invention wherein the conductors of the transducer are coupled to a waveguide of parallel conductor supported on a strip of dielectric material;

5 Figs. 5 and 6 are cross-sectional views taken along lines 5—5 and 6—6, respectively, of Fig. 4;

Fig. 7 is a view in plan of a modified form of coupling arrangement between a waveguide of parallel conductors and the conductors of the transducer;

10 Fig. 8 is a view in side elevation with parts broken away showing a modified form of the coupling arrangement illustrated in Figs. 4 and 7;

Fig. 9 is a view in cross-section taken along line 9—9 of Fig. 8;

15 Fig. 10 is a cross-sectional view similar to Fig. 9 showing a slight variation of the parallel conductor waveguide that may be employed; and

20 Fig. 11 is a view in plan of a further embodiment of the invention showing a transducer arrangement coupling a coaxial line to a single conductor waveguide.

25 Referring to Figs. 1 and 2 of the drawing, the transducer of the present invention is shown to comprise a first conductor 1 of elongated form and a second conductor 2 of planar form spaced apart by a layer of dielectric material 3. The planar conductor 2 as well as the layer of dielectric material is made wider than the conductor 1 so that radio frequency waves may be propagated there-

along in a mode having some properties of the TEM mode. Wave energy from a coaxial waveguide is coupled 30 to this type of parallel waveguide by providing the planar conductor 2 with an opening 4 about which is coupled the outer conductor 5 of a coaxial waveguide 6. The inner conductor 7 is extended through the opening 4 and is connected directly to the elongated conductor 1 as

35 indicated at 8. The transducer may have coupled thereto as an extension thereof a waveguide of parallel conductors as indicated by conductors 1a and 2a and dielectric layer 3a. The conductor 2a is disposed in parallel relation to the conductor 1a on the same side of the di-

40 electric layer 3a. These conductors may be formed by known printed circuit technique, additional information on which may be obtained by reference to the copending application of M. Arditi-P. Parzen, Serial No. 286,764, filed May 8, 1952, now U. S. Patent No. 2,774,046. The

45 conductor 2a is preferably extended in overlying parallel relation to the planar conductor 2, the conductor 2a being angled away from conductor 1 as indicated at 9 and terminated by a layer of attenuating material 10 disposed thereon. The planar characteristic of conductor 2 is pref-

50 erably terminated a short distance from the coupling opening 4, the termination preferably being in a taper as indicated at 2c.

55 While the propagation of wave energy from the coaxial waveguide 6 to the transducer conductors 1, 2 is performed readily in similar modes, the transfer of the wave energy from the conductors 1, 2, to conductors 1a,

2a, undergoes an angular translation through 90°. It will be understood from the view of Fig. 1 that the electric field is substantially normal to the conductors 1 and

60 2 and in the angular translation must shift so as to be normal to the edge portions of the two conductors 1a, 2a. The electromagnetic field thus assumes a mode of propa-

65 gation characteristic of parallel lines completely immersed in dielectric even though the two conductors are supported on the same side of a strip of dielectric material, it being understood, of course, that there will be some variation in the field distribution in view of the difference between the dielectric coefficient of the dielectric material

70 and open space.

While the conductors 1a and 2a are shown to have a space therebetween of d_1 it will be readily apparent that

this spacing may be varied to a much larger spacing d_2 as indicated in Fig. 3, depending upon the characteristic impedance desired for the parallel waveguide. The larger the spacing between conductors the greater the characteristic impedance and the lower the attenuation of the line. In tests of two parallel conductor strips each 9 mm. wide supported on a strip of fiberglass 25 mm. wide and 1.5 mm. thick, the losses varied as follows for the different spacings indicated, a frequency of 4700 mc./sec. being employed for the tests:

Spacing (d)	Attenuation in db/meter
1 mm	3.5±0.2
2.5 mm	2.8±0.1
9 mm	1.6±0.1

In Figs. 4, 5 and 6 the transducer arrangement is shown wherein the angular translation of the electric field is avoided. The transducer is shown to include a first conductor 11 of elongated tapered form and a second conductor 12 of planar configuration separated by a layer of dielectric material 13. The two conductors 11 and 12 are both tapered toward the point of coupling to a parallel conductor waveguide, it being preferable to taper the two conductors to the dimension corresponding to that of the line conductors. This taper of conductor 12 terminates the planar characteristic thereof in the plane of the conductor 12 at its connection to one of the conductors of the parallel conductor waveguide. The dielectric layer may likewise be tapered although it could be left untapered, if desired. As shown in Fig. 4 the parallel line conductors comprise two strip conductors 14 and 15 carried on one side of a strip of dielectric material 16. The dielectric material 16 is disposed at right angles to the layer 13 and the spacing of the conductors 14 and 15 in this illustration is shown to be the same as the thickness of the layer 13. The conductors 14 and 15 are tapered as indicated at 14a and 15a so that the widths thereof correspond to the thickness of the conductors 11 and 12. It will be readily apparent from Fig. 4 that the wave energy is practically undisturbed in its propagation from conductors 11, 12 to conductors 14, 15, the tapered portions of the four conductors being gradual throughout with the transition. By providing a second transducer in series with conductors 14 and 15 the conductor 14 may be coupled to the second or "ground" conductor and conductor 15 to the first or line conductor, thus effecting polarity inversion.

In Fig. 7 the tapered portions 14b and 15b of strip conductors 14 and 15 are shown to overlap conductors 11 and 12. In this form the wave propagation is also practically undisturbed since the spacing between the conductors 11, 12 and conductors 14, 15 may be maintained substantially uniform while the two tapered portions are disposed in overlapping relation thus providing for a stronger joint than that shown in Fig. 4.

In Fig. 8 a coupling similar to that shown in Fig. 7 is illustrated wherein the conductors 17, 18 of the parallel conductor waveguide are embedded in a layer of dielectric material 19 and wherein the spacing between such conductors is greater than the spacing between the conductors 11, 12. The tapered portions 11b and 12b are wedged outwardly from the dielectric layer 13 by means of dielectric wedges 20 and 21. These wedges provide a support for the thin layers of conductive material forming the conductors 11b, 12b. While the conductors 17 and 18 may be embedded in dielectric material as shown in Figs. 8 and 9, some improvement is obtained by exposing the two conductors as indicated in Fig. 10 at 17a and 18a. For a 300 ohm television lead-in line with a spacing between centers of conductors 17 and 18 of 8 mm., a thickness of dielectric 19 at 1.5 mm., and an operating frequency of 4700 mc./sec. the attenuation was 1.1 ± 0.1 db/meter for the form shown in Fig. 9 and

0.9±0.1 db/meter for the form shown in Fig. 10. The wedge spread at 20, Fig. 8, and the taper of conductor 11, Fig. 4, also provide for coupling high impedance parallel conductor waveguides to relatively low impedance transducer arrangements, for example 300 ohms to 50 ohms.

The transducer shown in Fig. 11 provides for translation of wave energy propagated along a coaxial waveguide to a single conductor waveguide. The transducer structure is similar to the structures hereinabove described except that the elongated conductor 21 may be continued beyond the transducer as the single conductor waveguide 21a. The conductor 21 is spaced from the planar conductor 22 by a layer of dielectric material 23. The planar conductor 22, however, is provided with a slot 24 a short distance from the coaxial coupling indicated at 25, the slot being disposed in underlying relation to the elongated conductor 21. The edges of the planar conductor 22 defining the slot are flared outwardly from the conductor 21 as indicated at 26 and 27 thereby providing a translation of the mode of propagation between the conductors 21, 23 to a mode of propagation along the single conductor 21a. The single conductor 21a may be supported by a strip of dielectric as indicated at 23a or it may be supported in open air, whichever is desired. Such single line conductors operate satisfactorily as waveguides provided the resistivity thereof is of a proper value. To insure proper resistivity of the line it is sometimes desirable to coat the line with a dielectric material, such as enamel.

While I have described above the principles of my invention in connection with specific apparatus, it is to be clearly understood that this description is made by way of example only and not as a limitation to the scope of my invention as set forth in the objects thereof and in the accompanying claims.

I claim:

1. A transducer for radio frequency energy comprising a first conductor of elongated form, a second conductor disposed in dielectrically spaced substantially parallel relation to said first conductor, said second conductor being wider than said first conductor to present a planar surface in a given plane facing said first conductor, said second conductor having an opening therethrough, a coaxial waveguide disposed with the outer conductor thereof in electrical connection with said second conductor about said opening and the inner conductor thereof extended through said opening in electrical connection with said first conductor, said first conductor being extended from said opening for propagation of radio frequency waves therealong, said second conductor having at least the planar characteristic thereof in said given plane terminated a short distance from said opening by a tapered portion with the taper in the direction of the extension of said first conductor whereby radio frequency waves propagated along said coaxial waveguide is transferred for propagation along said first conductor.

2. A transducer according to claim 1, wherein said first conductor has associated therewith a third conductor of elongated form disposed in parallel relation thereto and constituting therewith a waveguide of parallel conductors, said third conductor being also disposed for a portion of its length in dielectrically spaced substantially parallel relation to said planar surface.

3. A transducer according to claim 2, wherein said third conductor has associated with said portion thereof a layer of attenuating material thereby terminating the conducting characteristic of said third conductor.

4. A transducer according to claim 1, wherein said second conductor has its said terminated planar characteristic with an elongated slot disposed in substantially parallel underlying relation to said first conductor with the sides of said slot flaring outwardly from said first conductor.

5. A transducer for radio frequency energy comprising

a first conductor of elongated form, a second conductor, a layer of dielectric material interposed between said first and second conductors to maintain them in spaced substantially parallel relation, said second conductor being wider than said first conductor to present a planar surface in a given plane facing said first conductor, said second conductor and said layer of dielectric material having openings extending therethrough in alignment with said first conductor, a coaxial waveguide disposed with the outer conductor thereof in electrical connection with said second conductor coaxially of said openings and the inner conductor thereof extended through said openings in electrical connection with said first conductor, said first conductor being extended from said opening for propagation of radio frequency waves therealong said second conductor having at least the planar characteristic thereof in said given plane terminated a short distance from said openings by a tapered portion with the taper in the direction of the extension of said first conductor whereby radio frequency waves propagated along said coaxial waveguide is transferred for propagation along said first conductor.

6. A transducer according to claim 5, wherein said first conductor has associated therewith a third conductor portion of elongated form disposed in parallel relation thereto and on the same side of said layer of dielectric material as said first conductor.

7. A transducer according to claim 5, wherein said second conductor has its said terminated planar characteristic thereof shaped to include an elongated slot disposed in substantially parallel underlying relation to said first conductor with the sides of said slot flared outwardly away from said first conductor.

8. A transducer according to claim 5, wherein said first and second conductors have joined contiguously thereto a waveguide of parallel conductors at a point of minimum width, the parallel conductors of said waveguide being maintained in parallel relation by a layer of dielectric material disposed at right angles to the plane of the layer of dielectric material interposed between said first and second conductors whereby the electric field propagation in a mode approximating the TEM mode along said first and second conductors is transferred for propagation along said parallel conductors in said TEM mode.

9. A transducer according to claim 8, wherein said parallel conductors are spaced apart a greater distance than the spacing between said first and second conductors, and dielectric wedge portions disposed on opposite sides of said first mentioned layer of dielectric material to support connecting lengths of conductors between the parallel conductors and said first and second conductors, respectively.

10. A transducer according to claim 8, wherein said waveguide of parallel conductors comprises two conductors in strip form carried by a layer of dielectric material, the width of said strip conductors being tapered with the tapered portions thereof disposed in overlapping relation to at least part of said first and second conductors.

11. A transducer for radio frequency energy comprising a first conductor of elongated form, a second conductor, a layer of dielectric material interposed between said first and second conductors to maintain them in spaced substantially parallel relation, said second conductor being wider than said first conductor to present a planar surface in a given plane facing said first conductor, said second conductor and said layer of dielectric material having openings extending therethrough in alignment with said first conductor, a coaxial waveguide disposed with the outer conductor thereof in electrical connection with said second conductor coaxially of said openings and the inner conductor thereof extended through said openings in electrical connection with said first conductor, said second conductor having at least the planar characteristic thereof in said given plane terminated a

short distance from said openings in the direction of extension of said first conductor whereby radio frequency waves propagated along said coaxial waveguide are transferred for propagation along said first conductor, said first and second conductors having coupled thereto a waveguide of parallel conductors, the parallel conductors of said waveguide being maintained in parallel relation by a layer of dielectric material disposed at right angles to the plane of the layer of dielectric material interposed between said first and second conductors, said first and second conductors being tapered to the parts thereof which are connected to said parallel conductors, the taper being such as to make the width of the first and second conductors correspond respectively to the thickness of said parallel conductors.

12. A transducer for radio frequency energy comprising a first conductor of elongated form, a second conductor, a layer of dielectric material interposed between said first and second conductors to maintain them in spaced parallel relation, said second conductor being wider than said first conductor to present a planar conductive surface in a given plane facing said first conductor, said second conductor having at least the planar characteristic thereof in said given plane terminated by a tapered portion with the taper in the direction of the extension of said first conductor, a waveguide of parallel conductors joined contiguously to said first and second conductors at a point of minimum width, the parallel conductors of said waveguides being maintained in parallel relation by a layer of dielectric material disposed at right angles to the plane of the layer of the dielectric material interposed between said first and second conductors, whereby the electric field propagation in a mode approximating the TEM mode along said first and second conductors is transferred for propagation along said parallel conductors in said TEM mode.

13. A transducer according to claim 12, wherein said parallel conductors are spaced apart a greater distance than the spacing between said first and second conductors, and dielectric wedge portions disposed on opposite sides of said first mentioned layer of dielectric material to support connecting lengths of conductors between the parallel conductors and said first and second conductors, respectively.

14. A transducer according to claim 12, wherein said waveguide of parallel conductors comprises two conductors in strip form carried by a layer of dielectric material, the width of said strip conductors being tapered with the tapered portions thereof disposed in overlapping relation to at least part of said first and second conductors.

15. A transducer for radio frequency energy comprising a first conductor of elongated form, a second conductor disposed in dielectrically spaced substantially parallel relation to said first conductor, said second conductor being wider than said first conductor to present a planar surface in a given plane facing said first conductor, said second conductor having an opening therethrough, a coaxial waveguide disposed with the outer conductor thereof in electrical connection with said second conductor about said opening and the inner conductor thereof extended through said opening in electrical connection with said first conductor, said first conductor being extended from said opening for propagation of radio frequency waves therealong, said second conductor having at least the planar characteristic thereof in said given plane terminated a short distance from said opening by a tapered portion with the taper in the direction of the extension of said first conductor whereby radio frequency waves propagated along said coaxial waveguide are transferred for propagation along said first conductor, and said first conductor has associated therewith a third conductor portion of elongated form disposed in parallel relation thereto to constitute a waveguide of parallel conductors, said third conductor constituting a continuation of said second conductor beyond the termination of said planar

characteristic in said given plane, whereby the electric field propagation in a mode approximating the TEM mode along said first and second conductors is transferred for propagation along said first and third conductors in said TEM mode.

16. A transducer for radio frequency energy comprising a first conductor of elongated form, a second conductor, a layer of dielectric material interposed between said first and second conductors to maintain them in spaced parallel relation, said second conductor being wider than said first conductor to present a planar conductive surface in a given plane facing said first conductor, said second conductor having at least the planar characteristic thereof in said given plane terminated by a tapered portion with the taper in the direction of the extension of said first conductor, a waveguide of parallel conductors coupled to said first and second conductors, the parallel conductors of said waveguides being maintained in parallel relation by a layer of dielectric material disposed at right angles to the plane of the layer of the dielectric ma-

terial interposed between said first and second conductors, whereby the electric field propagation in the mode approximating the TEM mode along said first and second conductors is transferred for propagation along said parallel conductors in said TEM mode, and said first and second conductors are tapered to the parts thereof which are connected to said parallel conductors, the taper being such as to make the width of the first and second conductors correspond respectively to the thickness of said parallel conductors.
